(No Model.)

M. E. DAYTON.

PAPER FILE.

No. 398,316.

Patented Feb. 19, 1889.

UNITED STATES PATENT OFFICE.

MELVILLE E. DAYTON, OF CHICAGO, ILLINOIS, ASSIGNOR TO CARL F. LOMB,
OF ROCHESTER, NEW YORK.

PAPER-FILE.

SPECIFICATION forming part of Letters Patent No. 398,316, dated February 19, 1889.

Application filed February 10, 1887. Renewed October 27, 1888. Serial No. 289,342. (No model.)

To all whom it may concern:

Be it known that I, MELVILLE E. DAYTON, of Chicago, in the county of Cook and State of Illinois, have invented certain new and useful Improvements in Paper-Files; and I do hereby declare that the following is a full, clear, and exact description thereof, reference being had to the accompanying drawings, and to the letters of reference marked thereon, which form a part of this specification.

This invention relates to paper-holding devices or files in which are employed two parallel arches to hold the papers, said arches being composed severally of a fixed and a movable wire, whereby the arches are adapted to be opened and closed to admit or discharge the papers.

The invention consists in the several matters hereinafter set forth, and pointed out in the claims.

In the accompanying drawings, Figure 1 is a perspective view of the operative parts of a file containing my improvement. Fig. 2 is a vertical section taken midway between the parallel arches. Fig. 3 is a top or plan view of the working parts of the file. Fig. 4 shows an alternative form of the adjacent ends of the wire which form each of the arches.

A represents a tablet or base of any character, commonly a thin board a little larger than the sheets to be filed.

B B are parallel and equal arches adapted to be opened and closed to permit papers to be applied to or removed from the file or transferred from one part of the arches to the other. The arches B are severally composed of the fixed vertical receiving-wires B' and the curved or arched transfer-wires B², the free ends of the transfer-wires being in alignment with the fixed wires when the file is closed, and either in actual contact therewith or proximate thereto, so that papers strung on the wires B' may be transferred to the wires B², or vice versa, in the familiar mode of use characteristic of this well-known class of files.

The invention here presented relates to the manner of moving the transfer-wires to permit the application of papers or a considerable number of papers to the receiving-wires

or the removal of the entire or a large part of the contents at one time, as when such contents are to be transferred to permanent filing-cases for preservation.

In former structures employing parallel two-part arches the transfer-wires or the receiving-wires have been hinged at the lower ends to the base or in vertical slots, or have been laterally movable along the base from or toward the other or stationary wires.

In one instance set forth in the patent to Shannon, No. 217,907, dated July 29, 1879, the arched transfer-wires are rotatable on their vertical axes in the base, and in another the arched wires are not only so rotatable, (separately,) but are bodily removable from the file by lifting them separately from sockets on the base in which their lower ends rest. In the construction last referred to the transfer-wires are separately held in the sockets of the base by set-screws, one holding each wire, and to bring and hold the arched wires in alignment at their free ends with the receiving-wires said arched wires are flattened on one side where the set-screws bear thereon.

The present invention contemplates a separation of the wires forming the several arches by a simultaneous vertical movement of both the arched transfer-wires B², and it does not involve the rotation or the vibration of said transfer-wires. The transfer-wires B² rest at their lower ends in sockets C in or upon the base, but are rigidly connected to each other above the sockets by a cross-bar, B³.

D is a spring-catch, which engages the cross-bar B³ to hold the transfer-wires down in proper relation to the receiving-wires to permit the transfer of papers from one to the other. It is also constructed, as here shown and as preferably employed, with a capacity for holding the transfer-wires at a little elevation above their normal or lowermost position to permit the free introduction of papers singly or in small numbers at a time, and this, it is suggested, will be the better position of the receiving-wires for convenience, except when it is desired to transfer the papers to the arched wires, in which case the latter will be lowered into juxtaposition with the receiving-wires.

E represents a spring or springs placed beneath the cross-bar B³, which, in this or some other form, is desirably present for the purpose of lifting the connected transfer-wires.

- 5 Then upon pressing the thumb against the upper end of the spring-catch D the cross-bar B³ automatically rises and engages the higher notch of said catch, so that the shifting of the position of the transfer-wires to 10 this more elevated position is an operation conveniently and quickly performed. The spring is, however, not indispensable, as the catch may itself sustain the transfer-wires.

I prefer to provide the catch D with an arm 15 projecting toward the plane of the receiving-wires in order that the catch may be more conveniently detached from the cross-bar when a body of papers occupies the transfer-wires and covers the catch proper.

- 20 The cross-bar may be located at any desired elevation on the transfer-wires and the sockets may be lengthened, so that the transfer-wires need not be wholly detached from the sockets or base in opening the arches for the 25 removal of the full contents of the file, though for some reasons the cross-bar is preferably placed lower and the transfer-wires are entirely removed from the file in removing its full contents, as here shown in the drawings.

- 30 The prolongation of the transfer-wires below the cross-piece B³ and the corresponding sockets on the base are convenient means for guiding the connected transfer-wires in their vertical movement and retaining them in 35 their vertical position at all points of their elevation; but any other form of interfitting projections and guides, of which many are familiar, will do as well.

I claim as my invention—

- 40 1. In a file having two severally-separable parallel wire arches, the combination, with a base and two receiving-wires, of two arched transfer-wires rigidly joined by a cross-piece, guides for the lower ends of the transfer-wires, 45 which permit vertical movement of said transfer-wires, and which retain them in a vertical

position at all points in their vertical movement, substantially as described.

2. In a file having two severally-separable parallel wire arches, the combination, with a 50 base and two receiving-wires, of two arched transfer-wires rigidly joined by a cross-piece above their lower ends, and vertical guides on the base fitted to the lower ends of the transfer-wires below the cross-piece, substantially 55 as described.

3. In a file having two severally-separable parallel wire arches, the combination, with a base and two receiving-wires, of two rigidly-connected arched transfer-wires, vertical 60 guides for said connected transfer-wires, which retain the latter in an upright position, and a catch having two notches or corresponding points of engagement, and which is adapted to hold the connected transfer-wires in two 65 positions, substantially as described.

4. The combination, with a base and two receiving-wires of a double-arch file, of two rigidly-joined arched transfer-wires, means for guiding said connected transfer-wires in 70 a vertical direction, a spring or springs arranged to exert a lifting force on the transfer-wires, and a catch arranged to hold the transfer-wires down in opposition to the action of the spring, substantially as described. 75

5. The combination, with a base and two receiving-wires of a double-arch file, of two rigidly-connected arched transfer-wires, means for guiding the connected transfer-wires in a vertical direction, a spring arranged 80 to bear upwardly upon the connected transfer-wires, and a double-notched spring-catch constructed to retain the transfer-wires in two positions in opposition to the action of the spring, substantially as described.

In testimony that I claim the foregoing as my invention I affix my signature in presence of two witnesses.

MELVILLE E. DAYTON.
